Specification for Design.

Patented Nov. 22, 1921.

Application filed April 19, 1921. Serial No. 462,708. Term of patent 3½ years.

To all whom it may concern:

Be it known that I, AUGUST J. ROTH, a citizen of the United States, residing at Mount Vernon, Westchester county, State of New York, have invented a new, original, and ornamental Design for a Trimming for an Automobile-Domelight or Similar Article of Manufacture, of which the following is a specification, reference being had to the accompanying drawing, forming a part thereof.

In said drawing:

Figure 1 is a front view of the trimming embodying my design.

Fig. 2 is an edge view of the same.

I claim—

The ornamental design for a trimming for an automobile domelight or similar article of manufacture substantially as shown.

AUGUST J. ROTH.
